His Attorney.

UNITED STATES PATENT OFFICE

RAY D. KELL, OF SCOTIA, NEW YORK, ASSIGNOR TO GENERAL ELECTRIC COMPANY, A CORPORATION OF NEW YORK

TRANSMISSION OF PICTURES

Application filed July 25, 1927. Serial No. 208,201.

My invention relates to the transmission of pictures, and has for its principal object the provision of an improved picture receiving apparatus which may be readily controlled to maintain it in synchronism with the apparatus by which the picture is transmitted.

In the transmission of pictures, it is essential that means be provided for successively scanning the elemental portions of the picture and for producing electrical impulses which are proportional to the intensity or color of the light emitted by these successive portions. It is also essential that means be provided for maintaining synchronism between the moving parts of the transmitting and receiving apparatus. When the picture is to be received by amateurs, it is especially desirable that the receiving apparatus be readily adjusted to operate in synchronism with any transmitting station desired. In accordance with my invention, this result is accomplished by the provision of an improved means for controlling the speed of the receiving apparatus and indicating the relation between this speed and the speed of the transmitting apparatus.

My invention will be better understood from the following description when considered in connection with the accompanying drawings and its scope will be pointed out in the appended claims.

Referring to the drawings, Fig. 1 illustrates a picture transmitting apparatus; and Fig. 2 illustrates a picture receiving apparatus wherein my invention has been embodied.

The transmitting apparatus illustrated by Fig. 1 comprises a rotatable drum 1 upon which the picture to be transmitted is mounted, an oscillation generating and amplifying device 2 of any suitable type, and an antenna 3 to which a high frequency carrier current is supplied from the device 2.

The drum 1 is geared to a driving motor 4 through a gear 5 mounted on the motor shaft 6 and a gear 7 mounted on the drum shaft 8 which is provided with a spline arranged to permit both rotation and endwise movement of the drum. Endwise

movement of the drum 1 is produced by a screw drive 9 which is geared to the motor 4 through gears 10 and 11. Under these conditions, rotation of the drum is produced by the gears 5 and 7 and endwise movement of the drum is produced by the gears 10 and 11.

A contact-making device comprising a slip ring 12 connected to a contact segment 13 embedded in the periphery of an insulation disk 14 is mounted on the shaft 8 and is connected to the device 2 for modulating the carrier current in accordance with the speed of the drum 1. This current is also modulated by electrical impulses dependent on the light transmitted from a source 15 through a lens 16 to the picture and reflected from the picture to a light responsive device such as a photo-electric cell 17 or the like. Thus assuming the motor 4 to be operating, the high frequency carrier current supplied to the antenna 3 from the device 2 is modulated both in accordance with the speed of the drum 1 and in accordance with the color of the elemental portions of the picture which is moved endwise so that these portions are successively subjected to the light of the source 15. It will be apparent that any other suitable picture transmitting apparatus may be used instead of that illustrated by Fig. 1.

The picture receiving apparatus illustrated by Fig. 2 comprises a radio receiving device 18 which is connected to an antenna 19 and is arranged to separate the modulating impulses produced respectively by the contact-making device of Fig. 1 and by the variation in the intensity of the light reflected from the elemental portions of the picture mounted on the drum 1. The modulating impulses produced by the contact making device are applied to a circuit which comprises a light 20 and a contact making device 21 which is similar to that of Fig. 1. The modulating impulses produced by variation in the color of the picture are applied to the operating coil of an oscillograph 22.

The picture receiving apparatus of Fig. 2 also comprises a drum 23 splined to a shaft 100

24 which is coupled to the shaft of a motor 25 through gears 26 and 27. Endwise movement of the drum 23 along the shaft 24 is produced through gears 28 and 29 which are interposed between the shafts of the motor and the drum. A disk 30 provided with an opening 31 is mounted on the motor shaft, and a key 32 is connected in shunt to a resistor 33 through which current is supplied to the field circuit of the motor 25.

In order that the picture mounted on the drum 1 may be reproduced on a light sensitive material mounted on the drum 23, it is essential that synchronism be maintained between the rotational movements of the drums and between the endwise movements of the drums. Equality in the speeds of the two drums is produced by the key 32 which is tapped or vibrated at such a speed as to vary the effect of the resistor 33 and raise or lower the speed of the motor 25 until the light of the lamp 20 is visible through the opening 31.

So long as light appears through the opening 31 when it passes the lamp 20, the transmitting and receiving apparatus are operating substantially in synchronism with one another and the light applied to the elemental portions of the drum 23 through the oscillograph 22 varies in accordance with the light reflected from the corresponding elemental portions of the picture mounted on the drum. If the speed of the motor 4 is constant, this of course requires that the key 32 be tapped at a substantially constant speed after the motor 25 has attained a speed corresponding to the motor 4. It has been found that the speed of the motor 25 may be readily adjusted to and maintained at any desired speed by an operator very slightly skilled in the use of the key. It will be apparent that this method of synchronizing the transmitting and receiving apparatus has the advantages that it does not require an expensive receiving apparatus and makes it possible for the ordinary amateur to receive pictures from different radio transmitting stations.

The embodiment of the invention illustrated and described herein has been selected for the purpose of clearly setting forth the principles involved. It will be apparent, however, that the invention is susceptible of being modified to meet the different conditions encountered in its use and I therefore aim to cover by the appended claims all modifications within the true spirit and scope of my invention.

What I claim as new and desire to secure by Letters Patent of the United States, is:—

1. A picture receiving apparatus comprising means for receiving and separating a plurality of electrical impulses each having successive maximum and minimum values, means for driving said apparatus, a mem-

ber arranged to be manually vibrated for controlling the speed of said driving means, and means for indicating when said driving means is operating at a speed in synchronism with the variations in the magnitude of one of said impulses. 70

2. A picture receiving apparatus comprising means for receiving and separating a plurality of electrical impulses each having successive maximum and minimum values, means for driving said apparatus, manually operated means for controlling the speed of said driving means, means including a perforated disk arranged to be rotated by said driving means and a light source controlled by one of said impulses for indicating when said driving means is operated at a speed in synchronism with the variations in the magnitude of one of said impulses, and means arranged to produce light of an intensity which varies in accordance with another of said impulses. 75 80 85

3. A picture receiving apparatus comprising means for receiving and separating a plurality of electrical impulses each having successive maximum and minimum values, means for driving said apparatus, a member arranged to be manually vibrated for controlling the speed of said driving means, means for indicating when said driving means is operated at a speed in synchronism with the variations in the magnitude of one of said impulses, means arranged to produce light of an intensity which varies in accordance with another of said impulses, and means operated by said driving means for producing a record dependent on the intensity of said light. 90 95 100

4. The combination of a picture transmitting apparatus operable to transmit electrical impulses which are respectively dependent on the speed of said apparatus and on the variation in the color of the successive elemental portions of the picture to be transmitted, and a receiving apparatus comprising means for receiving and separating said impulses, means for driving said receiving apparatus, a key for controlling the speed of said driving means, and means for indicating when said driving means is operated in synchronism with variations in the magnitude of the impulse dependent on the speed of said transmitting apparatus. 105 110 115

5. The combination of a picture transmitting apparatus operable to transmit electrical impulses which are respectively dependent on the speed of said apparatus and on the variation in the color of the successive elemental portions of the picture to be transmitted, and a receiving apparatus comprising means for receiving and separating said impulses, means for driving said receiving apparatus, a key for controlling the speed of said driving means, a disk arranged to be rotated by said driving means and pro- 120 125 130

vided with an opening, and a light alined with the path of said opening and arranged to be subjected to the impulses dependent on the speed of said transmitting apparatus.

In witness whereof, I have hereunto set
5 my hand this 22nd day of July, 1927.

RAY D. KELL.
